UNITED STATES PATENT OFFICE

NORMAN L. DONOVAN, OF JERSEY CITY, NEW JERSEY, ASSIGNOR TO GENERAL RAILWAY SIGNAL COMPANY, OF ROCHESTER, NEW YORK

INTERLOCKING SYSTEM FOR RAILROADS

Application filed December 5, 1929. Serial No. 411,823.

This invention relates to interlocking systems for railroads, and more particularly pertains to circuits and devices used to accomplish the control of the switch machines employed in such interlocking systems.

In an interlocking plant, it is desirable to control the various traffic controlling functions from a central tower, so that the traffic may be as nearly as possible under the supervision of a single operator. However, the usual type of interlocking machine, employed in the interlocking tower to control the distant traffic controlling functions, sometimes assumes such a size as to require several operators or levermen to act under the orders of a single supervisor. Also, this type of interlocking machine has the control levers interrelated by the usual mechanical interlocking between levers as well as containing the various circuit controllers, selectors, time contactors, indication latches, and the like, which add to the bulk of the machine.

The present invention proposes to provide an interlocking system with a type of centralized control that may be conveniently termed "push button control" which provides a great economy in space for the control board and multiplies the number of functions which one operator may adequately supervise. The present invention provides that the circuit controllers, locks, selectors, and the like, may be located in a room or building adjoining the operating room.

A further object of the invention is to provide this type of "push button control" and still employ the principles of control which are used with the four position type control lever in connection with the operation of power operated switch machines. This object is accomplished by the provision of suitable electromagnetic circuit controllers and locks both in the central tower and at the switch locations, and indication means indicating the completion of an operation of a track switch as well as its position and locked condition.

Other objects, purposes and characteristic features of the present invention will be in part obvious from the accompanying draw-

ings, and in part pointed out as the description of the invention progresses.

In describing the invention in detail, reference will be made to the accompanying drawings, in which Figs. 1 and 1A, when placed end to end, represent in a diagrammatic manner the circuits and devices arranged and constructed according to the present invention to accomplish the control of a single track switch.

With reference to the accompanying drawings, a track switch TS is shown as operated by a suitable switch machine SM which may be of the type, for example, such as shown in the patent to W. K. Howe No. 1,466,903 dated September 4, 1923. This switch machine SM is shown in the conventional manner as including an armature A, a field winding F, pole changer contacts PC, pole changer coil contacts PCC, and point detector contacts PD. This switch machine operates in a manner as set forth in the above mentioned Patent No. 1,466,903 with its operating circuits adapted to the present invention.

The pole changer contacts PC include movable contacts 5 and 6 which make connection between certain pairs of fixed contacts when in normal positions and between certain other pairs of fixed contacts when in reverse positions. These movable contacts 5 and 6 are caused to assume normal positions at the end of the operation of the switch machine to a normal position, and are caused to assume reverse positions at the end of the operation of the switch machine to a reverse position, or are operated to an opposite extreme position during mid-stroke of the switch machine due to the reversal of the control, which is accomplished by suitable energization of the pole changer coils 7 and 8.

The pole changer coil contacts PCC include movable contacts 9 and 10. The movable contact 9 makes contact between a pair of fixed contacts when in a normal position or when in an intermediate position, while the movable contact 10 makes contact between a pair of fixed contacts when in a reverse position or when in an intermediate position. These movable contacts 9 and 10

assume normal or reverse positions in correspondence with the switch machine SM, and assume intermediate positions during the operation of the track switch TS from one 5 extreme position to another extreme position.

The point detector contacts PD include 10 movable contacts 14 and 15 which assume normal or reverse extreme positions in correspondence with track switch TS when it is locked, and assume intermediate positions during the operation of the track switch TS or at such other times that it is unlocked. These contacts 14 and 15 make contact between their respective pairs of fixed contacts when in normal extreme positions, and 15 make contact between certain other pairs of fixed contacts when in reverse extreme positions.

Located at the switch machine is a remote 20 controller RCR for governing the supply of operating energy to the switch machine SM from a local source of electrical potential, the positive and negative terminals of which are conveniently designated B+ and B- respectively. The remote controller RCR is provided with normal and reverse operating coils 16 and 17 respectively which operate a contact rod 18 to either of two extreme positions depending upon the coil last energized. This contact rod 18 carries movable contact members which make connection between their respective pairs of fixed contacts either when in normal positions or 25 reverse positions as will be more specifically pointed out hereinafter. The contact rod 18 is provided with a projection 18^a which is engaged by a lock rod 19 that is operated to a non-engaging position by a lock coil LC and is returned to an engaging position 30 by either of two indication coils 21 or 22. The lock rod 19 may engage the projection 18^a when it is in either normal or reverse position, maintaining the contact rod 18 in such position until the lock rod 19 is actuated to a non-engaging position. This lock 35 rod 19 further carries movable contacts which make contact between their fixed pairs of contacts either with the lock rod in a normal locking position or in an unlocked (non-engaging) position in accordance with the function to be accomplished.

It will be noted, throughout the description of the embodiment of the present invention, that the opposite terminals of all 40 sources of electrical potential will be designated as B+ and B-, which sources may be the same sources of supply or other suitable sources all in accordance with the practical application of the invention. It is to be understood that these sources of electrical potential for operation of the switch machine SM and other devices are preferably local to the switch machine and the points 45 indicated; also, they may be of either direct

current or alternating current according to the circumstances to be met in practice.

In the interlocking tower, a miniature track diagram, identical in every respect to the actual track layout in the interlocking plant, is shown as including the track switch ts beneath which are normal and reverse indicator lamps N and R respectively which indicate the position and locked condition of the associated track switch TS. Beneath these two indicator lamps N and R are located two self-restoring push buttons PN and PR having restoring means, as springs s, which accomplish the control of the track switch TS to normal or reverse positions respectively. 70

A selector S of the electromagnetic mechanical stick type is provided for maintaining the condition established by the momentary depression of either of the two push buttons PN and PR. 75

The actual control of the distant remote controller RCR and switch machine SM is accomplished by a circuit controller CR which may be located at any convenient point in the interlocking tower and includes normal and reverse operating coils 24 and 25 respectively for operating a contact rod 28 to either of two extreme positions. This contact rod 28 carries movable contacts for interconnecting their respective pairs of fixed contacts in accordance with the positions assumed, as hereinafter described. The lock rod 28 carries a projection 28^a which is engaged by a self-restoring locking member 29, that is, the locking member 29 normally assumes an engaging position due to some suitable biasing means, shown as a coil spring, except when actuated to a non-engaging position by a controller lock coil 30. This locking member 29 also carries a movable contact for making contact between a pair of fixed contacts when in a normal biased position and between another pair of fixed contacts when in an actuated or unlocked position. 90 100

Also, located in the interlocking tower, is a relay SS for indicating the position and locked condition of the associated track switch TS, the correspondence with said track switch TS of the remote controller RCR, and the completion of an operation of the switch machine. This SS relay has associated therewith a repeater relay SR for purposes to be hereinafter set forth. 115

A lock relay LR is controlled by the track repeating relay TR associated with the track section in which the track switch TS is located, and by the various other sectional locking and route locking relays (not shown) usually employed for electrically interlocking the various traffic controlling functions of interlocking plants. 120 125

It is believed, that the usefulness and the various interrelated functions of the devices 130

and circuits of this specific embodiment of the present invention will be more readily understood by further description being given from the standpoint of operation.

5 *Operation of the system.*

The interlocking system is shown in a full normal position with the track switch TS in a normal locked position, which is indicated in the interlocking tower by the illumination of the indicator light N located beneath the track diagram. The remote controller RCR is in a normal locked condition which prevents the switch machine SM from being operated, due to the dynamic indication circuit, until the lock coil LC has been properly energized. This cannot occur unless the lock relay LR located in the interlocking tower is energized, when a push button for controlling the track switch TS to a new position, is depressed.

More specifically, the switch machine SM is prevented from operation by the application of unauthorized current, due to the dynamic indication or braking circuit which is completed at the end of the normal and reverse operations of the switch machine. The normal dynamic braking circuit is traced as follows:—from the upper terminal of armature A, through wire 33, contacts 5—34, wires 35, 36 and 37, indication coil 21, wire 38, normal contact 39 of remote controller RCR, wires 40, 41 and 42, field winding F, wires 43 and 44, contacts 6—45, wires 46 and 47, to the lower terminal of the armature A.

The lock rod 19 is in an engaging position in respect to the contact rod 18, as a result of which energy is applied to the point detector contacts PD which indicate the normal position and locked condition of track switch TS by energizing the SS relay in the interlocking tower with current of a normal polarity. This normal energizing circuit for the SS relay is traced as follows:—from the positive terminal of a suitable source of electrical potential indicated as B+, through normal contact 50 of remote controller RCR, wires 51 and 52, contacts 14—54, wires 55 and 56, winding of SS relay, wire 57, contacts 15—58, wires 59 and 60, normal contact 61 of remote controller RCR, to the negative terminal of the suitable source indicated as B—. The energization of the contacts of the SS relay to right-hand normal positions results in the energization of the relay SR and the indicator lamp N.

The relay SR is energized through a normal circuit traced as follows:—from the positive terminal of a suitable source of electrical potential indicated as B+, through normal contact 64 of selector S, wire 65, normal contact 66 of controller CR, wire 67, normal contact 68 of relay SS, wire 69, winding of relay SR, to the negative terminal of the suitable source indicated as B—. The

attraction of the contact 94 of relay SR de-energizes the circuit for the lock coil 30, which in turn allows the energization of the normal indicator lamp N. The energizing circuit for the indicator lamp N is traced as follows:—from the positive terminal of a suitable source of electrical potential indicated as B+, through front contact 71 of lock relay LR, wire 72, normal contact 73 of relay SS, wire 74, indicator lamp N, wire 75, normal contact 76 of controller CR, to the negative terminal of the suitable source indicated as B—.

It will be noted, that throughout the description of the specific embodiment of the present invention, the lock relay LR is assumed to be energized in accordance with proper conditions of the detector track section associated with the track switch TS and the various other sectional and route locking relays associated therewith. The lock relay LR is shown to indicate the point of interconnection between the present invention and the interlocking circuits of usual practice to be associated therewith.

Let us now assume that the operator desires to operate the track switch from a normal locked position to a reverse locked position. To accomplish this result, the operator depresses the push button PR which actuates the contacts of the selector S to reverse positions if the lock relay LR is properly energized according to the condition of the associated detector track sections and route locking relays and the like. As soon as the selector is operated, energy is placed upon the wire 88 which energizes the lock coil LC. At the same time, the operation of the selector contacts to reverse positions opens the energizing circuit of the relay SR which, when deenergized, energizes the lock coil 30 of the controller CR if the lock relay LR is still energized. This actuates the locking member 29 to a non-engaging position closing the circuit at that time for the reverse operating coil 25 of the controller CR. The contact rod 28 is then operated to a reverse position closing a circuit for energizing the reverse operating coil 17 of the remote controller RCR (for the circuits involved, see below). As the lock rod 19 of the remote controller RCR is now in an energized position, the contact rod 18 is operated to a reverse position. Thus, energy is placed upon the reverse operating wire of the switch machine SM which causes it to operate the track switch TS to a reverse locked position.

When the switch machine has completed the operation of the track switch, it has free movement or free run at the end of the operating stroke which generates a dynamic current that flows through the coil 21 to actuate the lock rod 19 back to an engaging locked position, as well as dynamic

cally braking the motor armature. The reverse energizing circuit for the SS relay is now completed which indicates in the tower the completion of the operation of the track switch TS by illumination of the indicator light R after the energization of the relay SR which deenergizes the lock coil 30 of the controller CR resulting in the release of the locking member 29 to lock the contact rod 28 of the controller CR in a reverse position.

Considering the operation in greater detail, the energizing circuit for the reverse operating coil of the selector S is traced as follows:—from the positive terminal of a suitable source of electrical potential indicated as B+, through front contact 71 of lock relay LR, wires 71, 78, 79 and 80, depressed push button PR, wire 81, reverse operating coil 82 of selector S, to the negative terminal of the suitable source indicated as B-. The contacts of the selector S are operated to reverse positions, which results in the deenergization of the relay SR with its circuit as heretofore traced opened at normal contact 64 of selector S. Also, as soon as the contact 64 of selector S reaches a reverse position, a circuit is completed for energizing the lock coil LC of the remote controller RCR. This energizing circuit for the lock coil LC is traced as follows:—from the positive terminal of a suitable source of electrical potential indicated as B+, through reverse contact 64 of selector S, wires 84 and 85, normal contact 86 of controller CR, wires 87 and 88, winding of lock coil LC, wires 89 and 90, front contact 91 of lock relay LR, to the negative terminal of the suitable source indicated as B-. The lock rod 19 is operated to a non-engaging position opening the normal energizing circuit of the SS relay at normal contacts 50 and 61 and closing a circuit for energizing the reverse operating coil 17 of remote controller RCR as soon as the controller CR is operated to a reverse position.

The energization of the lock coil 30 of the controller CR is completed, as soon as relay SR is deenergized through a circuit traced as follows:—from the positive terminal of a suitable source of electrical potential indicated as B+, through front contact 71 of lock relay LR, wires 78 and 92, lock coil 30, wire 93, back contact 94 of relay SR, wires 95 and 90, front contact 91 of relay LR, to the negative terminal of the suitable source indicated as B-. The locking member 29 is actuated to a non-engaging or unlocked position in which the normal contact 76 is opened and "unlocked" contact 76 is closed which energizes the reverse operating coil 25 of controller CR to operate the contact rod 28 to a reverse position.

65 The reverse operating circuit of the con-

troller CR is traced as follows:—from the positive terminal of the suitable source of electrical potential indicated as B+, through unlocked contact 76 of controller CR, wire 96, reverse contact 97 of selector S, wire 98, reverse operating coil 25 of controller CR, to the negative terminal of the suitable source indicated as B-. The contact rod 28 is operated to a reverse position which opens the energizing circuit for the lock coil LC at the normal contact 86 and closes the energizing circuit for the reverse operating coil 17 of the remote controller RCR at reverse contact 100.

70 The reverse energizing circuit for the remote controller RCR is traced as follows:—from the positive terminal of a suitable source of electrical potential indicated as B+, through reverse contact 100 of controller CR, wire 101, reverse operating coil 17 of remote controller RCR, wire 102, unlocked contact 103 of remote controller RCR, wires 104, 89 and 90, front contact 91 of lock relay LR, to the negative terminal of the suitable source indicated as B-. The contact rod 18 of remote controller RCR is operated to a reverse position in which the reverse operating circuit of the switch machine SM is completed causing it to operate the track switch TS from a normal locked position to a reverse locked position in the usual well known manner.

75 The reverse operating circuit of the switch machine SM is traced as follows:—from the positive terminal of the suitable source of electrical potential indicated as B+, through reverse contact 107 of remote controller RCR, wires 108, 36 and 35, contacts 5-34, wire 33, armature A, wires 47 and 46, contacts 6-45, wires 44 and 43, field winding F, wires 42, 41 and 109, reverse contact 110 of remote controller RCR, to the negative terminal of the suitable source indicated as B-. The switch machine SM now operates, and as soon as the track switch TS is unlocked, the movable contacts 9, 10, 14 and 15 are operated to intermediate positions.

80 With the movable contacts 9 and 10 of the pole changer coil contacts PCC in intermediate positions, the switch machine SM could be reversed in mid-stroke as the movable contact 10 closes a circuit which, if energized by the remote controller RCR, would energize the pole changer coils 7 to operate the movable contacts 5 and 6 to reversed positions to cause the switch machine to operate in an opposite direction. This is accomplished in the usual manner and need not be explained in detail.

85 Assuming that the switch machine SM continues to operate the track switch TS, the movable contacts 5 and 6 are operated to extreme reverse positions at the comple-

tion of the operating stroke, while the movable contacts 9, 10, 14 and 15 are operated to reverse extreme positions as soon as the track switch TS is locked.

5 When the movable contacts 5 and 6 reach their reverse extreme positions due to their operation by the switch machine SM, a reverse snubbing or dynamic braking circuit is completed, which causes energy to flow through the indication coil 22. This circuit, as well as braking the motor of the switch machine, also serves to operate the lock rod 19 to an engaging position which prevents any further movement of the contact rod 18 of remote controller RCR, until it is again unlocked.

This reverse dynamic braking or snubbing circuit for the remote operation of the switch machine SM is traced as follows:—from the upper terminal of the armature A, through wires 33 and 111, contacts 5—112, wires 113, 114 and 115, indication coil 22, wire 116, reverse contact 117 of remote controller RCR, wires 118, 119, 120 and 43, field winding F, wires 42 and 121, contacts 6—122, wire 47, to the lower terminal of armature A. The dynamic current of the switch machine flows in indication coil 22 and is effective, as heretofore mentioned, to operate the lock rod 19. The energizing circuit for the reverse operating coil 17 of remote controller RCR is now opened at unlocked contact 103. As the movable contacts 14 and 15 of the point detector contacts PD are in reverse extreme positions energy is applied to the SS relay through a reverse energizing circuit with the contacts 61 and 50 in normal positions. This reverse energizing circuit for the SS relay is traced as follows:—from the positive terminal of a suitable source of electrical potential indicated as B+, through normal contact 50 of remote controller RCR, wire 51, contacts 15—123, wires 124 and 57, winding of SS relay, wires 56 and 125, contacts 14—126, wire 60, normal contact 61 of remote controller RCR, to the negative terminal of the suitable source indicated as B-. The contacts 68 and 73 of the SS relay are thus energized to reverse left-hand positions in which the reverse energizing circuit for the relay SR is completed. The reverse energizing circuit for relay SR is traced as follows:—from the positive terminal of a suitable source of electrical potential indicated as B+, through reverse contact 64 of selector S, wires 84 and 128, reverse contact 129 of controller CR, wire 130, reverse contact 68 of relay SS, wire 69, winding of relay SR, to the negative terminal of the suitable source indicated as B-. The contact 94 of relay SR is actuated to an energized position which opens the energizing circuit of the lock coil 30 of the controller CR at back contact 94 as is obvious from the drawings.

The locking member 29 of controller CR now assumes a locked position engaging the contact rod 28 preventing its movement. The energizing circuit for the reverse operating coil 25 of the controller CR is opened at “unlocked” contact 76, while the energizing circuit for the indicator lamp R is now completed with the SS relay indicating the reverse locked position of the track switch TS. This energizing circuit for the indicator lamp R is traced as follows:—from the positive terminal of a suitable source of electrical potential indicated as B+, through front contact 71 of relay LR, wire 72, reverse contact 73 of relay SS, wire 131, indicator lamp R, wire 75, normal contact 76, to the negative terminal of the suitable source indicated as B-.

The operation of the interlocking system shown as the specific embodiment of the present invention, has been described from its normal condition to its reverse condition which is deemed sufficient to point out the features of the present invention without describing the operation of the system from a reverse condition to a normal condition, which is merely an inverse function of the operation already described.

The system is shown and described in the manner in which it is normally operated but varying conditions in practice may alter the constants of the operation in a manner to require certain changes in designed details. For example, the lock coil LC actuates its lock rod 19 to an unlocked position during the time that the relay SR is becoming de-energized. However, should the distance between the controller CR in the interlocking tower and the remote controller RCR at the switch machine be so great that the action of the resistance and impedance of the line wires would be so effective as to retard the actuation of the lock rod 19 by lock coil LC, the relay SR may be made slow acting in accordance therewith to provide that the remote controller RCR may positively be unlocked before the controller CR operates to deenergize the lock coil LC.

Having described one rather specific embodiment of the present invention, it is to be understood that the various circuits and devices, included within the embodiment, are used to facilitate in the disclosure of the invention rather than to limit the number of forms which the invention may assume; also, it is to be understood that various modifications, adaptations and alterations may be made to the interlocking system embodying the present invention to meet the varying requirements of practice without departing from the spirit or scope of the invention as set forth in the appended claims.

Having described my invention, I now claim:—

1. In an interlocking system for railroads, a track switch, a switch machine having normal and reverse operating circuits, electromagnetic contactor means for closing said normal or said reverse operating circuit, and self-restoring push button means for causing operation of said contactor means. 70
2. In an interlocking system for railroads, a switch machine having a normal operating circuit and a reverse operating circuit, a two-position contactor for closing said normal operating circuit when in one position and for closing said reverse operating circuit when in the other position, one self-restoring push button for operating said contactor to one position, another self-restoring push button for operating said contactor to the other position, and means preventing operation of said contactor except in accordance with 75 traffic conditions. 80
3. In an interlocking system for railroads, a switch machine having a normal operating circuit and a reverse operating circuit, a two-position contactor for closing said normal operating circuit when in one position and for closing said reverse operating circuit when in the other position, one self-restoring push button for operating said contactor to one position, another self-restoring push button for operating said contactor to the other position, a locking member for preventing operation of said contactor, means for actuating said locking member to a non-locking position, said means being operable in accordance with traffic conditions when said one or said other push button is depressed, and means actuating said locking member to a locking position, said means being operated by dynamic current generated by the free run of said switch machine. 85 90
4. In an interlocking system for railroads, a switch machine having a normal operating circuit and a reverse operating circuit, a two-position contactor for closing said normal operating circuit when in one position and for closing said reverse operating circuit when in the other position, a locking member for preventing operation of said contactor, a lock coil for actuating said locking member to a non-locking position, means for actuating said locking member to a locking position, said means controlled by the dynamic indication current of said switch machine, one self-restoring push button for operating said contactor to one position, another self-restoring push button for operating said contactor to an opposite position, and means associated with said one and said other push button for executing the operation of said contactor to a new position as initiated by either of said push buttons. 95 100 105
5. In an interlocking system for railroads, a switch machine having a normal operating circuit and a reverse operating circuit, a two-position contactor for closing said normal operating circuit when in one position and for closing said reverse operating circuit when in the other position, a locking member for preventing operation of said contactor, a lock coil for actuating said locking member to a non-locking position, means for actuating said locking member to a locking position, said means controlled by the dynamic indication current of said switch machine, a two-position mechanical stick type selector for operating said contactor to one or the other of its positions, one self-restoring push button for operating said selector to one position, and another self-restoring push button for operating said selector to the other position. 110 115 120
6. In an interlocking system for railroads, a switch machine having a normal operating circuit and a reverse operating circuit, a two-position contactor for closing said normal operating circuit when in one position and for closing said reverse operating circuit when in the other position, a locking member for preventing operation of said contactor, a lock coil for actuating said locking member to a non-locking position, means for actuating said locking member to a locking position, said means controlled by the dynamic indication current of said switch machine, a two-position controller for operating said contactor to one or the other of its positions, a lock normally preventing operation of said controller, means active to release said lock when said controller is out of correspondence with said contactor, a two-position mechanical stick type selector for operating said controller to one or the other of its positions, one self-restoring push button for operating said selector to one position, another self-restoring push button for operating said selector to the other position, means preventing operation of said selector except in accordance with traffic conditions, means energizing said lock coil when said selector is out of correspondence with said controller, means indicating the position and locked condition of said switch machine, and means indicating the correspondence of said selector, said controller with said switch machine. 125 130 135
7. In an interlocking system for railroads, a track switch, a switch machine having a normal operating circuit and a reverse operating circuit, one self-restoring, normally open, push button for closing said normal operating circuit, another like push button for closing said reverse operating circuit, and means for accomplishing the control of said switch machine as initiated by said one and said other push buttons. 140
8. In an interlocking system for railroads, a track switch, a switch machine having a normal operating circuit and a reverse operating circuit, contacting means for closing 145

5 said normal operating circuit and opening
said reverse operating circuit when in a
normal position or closing said reverse op-
erating circuit and opening said normal op-
erating circuit when in a reverse position,
means for operating said contacting means
to a normal position, means for operating
said contacting means to a reverse position,
a lock normally preventing operation of said
10 contacting means to a new position, means
releasing said lock in accordance with traffic
conditions when said normal or said reverse
operating means for said contact means is
actuated, and means operating said lock to
15 a locked condition, said means being actuated
by the dynamic current of said switch
machine.

In testimony whereof I affix my signature.
